UNITED STATES PATENT OFFICE.

ALBERT HEMSHEWSKI, OF COAL VALLEY, ILLINOIS, ASSIGNOR OF ONE-FIFTH TO
EGNATY SHUMILO, OF NEFFS, OHIO.

TABLE.

1,427,383.

Specification of Letters Patent. Patented Aug. 29, 1922.

Application filed September 15, 1920. Serial No. 410,354.

To all whom it may concern:

Be it known that I, ALBERT HEMSHEWSKI, a citizen of Russia, residing at Coal Valley, county of Rock Island, and State of Illinois, 5 have invented certain new and useful Improvements in Tables, of which the following is a specification.

This invention relates to improvements in tables, particularly tables for self-service 10 and it is the principal object of the invention to provide a table of this character which allows a diner to select and place within his easy reach any dish on the table without disturbing his co-diners or needing 15 the assistance of a servant.

The invention has a special utility in connection with lunch or dining rooms and the like in which food dishes or the like, may be placed upon the center rotatable part of the 20 table so that a guest may turn the special dish he prefers within easy reach of his hands.

Another object of the invention is to provide a table which can be conveniently used 25 as a pay table or as a table for filing.

For the purpose of accomplishing the above objects certain novel structure is employed as will be more fully set forth hereinafter.

30 Referring to the drawings which are for illustrative purposes only:

Figure 1 is a top plan view of a table constructed according to the present invention.

35 Figure 2 is a side view of the table, partly in section.

Figure 3 is a top plan view of the table-support, partly in section along line 3—3 of Figure 2.

40 Figure 4 is a top plan view of a modified form of table constructed according to the present invention, and

Figure 5 is a side view thereof.

As illustrated in Figures 1, 2 and 3, the 45 table comprises the customary plate 10 resting upon a supporting square frame 11 provided with the cross-braces 12, 13, 14 and 15, the central meeting ends of which are constructed to form a supporting ring 16 on a bearing 17, provided with a central hole 18, for the passage of the central leg 19, the upper end of which carries a round table 20, the outer edge of which is somewhat higher than the plane of the plate 10, and which is

adapted to rotate on said leg within a circular opening in the center of the table plate 10. The lower end of the leg 19 is journaled in a bearing 21 in the middle of a brace 22 between the table legs 23 and 24. As shown in Figure 1, dishes 25, 26, 27, 28 and 29 may be placed upon the center rotatable table 20, so that a person can bring any of the dishes within easy reach of his hands by gripping the outer edge of the plate 20.

As illustrated in Figures 4 and 5, the 65 table, especially the center part thereof, may be constructed to contain a plurality of drawers 30 provided with outer knobs 31 which are adapted to be pulled out over the plate 10 and these drawers may be used for 70 the reception of pay envelopes, each for a certain denomination, as for instance one drawer for envelopes containing \$20.00 the other for those containing \$30.00 or \$25.00 according to the scale of the weekly wages to 75 be paid out. These drawers may also just as well be used for filing away letters, documents or the like, and may be correspondingly labelled.

All these described uses are obviously 80 within the scope of my invention and it is to be understood are described as illustrative only.

Having thus described my invention, what I claim is:

85 A table of the character described comprising a round top plate having a central opening, a square support for said top plate, cross-braces connecting the sides of said square support, a central supporting ring, a bearing carrying said ring and provided with an opening formed at the inner meeting ends of said braces, an auxiliary table plate, a leg secured to the underside of said auxiliary table plate, legs for said square 90 support, lower braces for said legs adapted to have the lower end of said leg of the auxiliary table journaled therein, said auxiliary table adapted to carry dishes and to be gripped by hand at its periphery projecting 95 above the top plate for rotating said auxiliary table and the dishes thereon for bringing any of said dishes in front of a person at the round top plate.

In testimony whereof I have affixed my 100 signature.

ALBERT HEMSHEWSKI.
